United States Patent Office.

SIMON WING, OF BOSTON, ASSIGNOR TO HIMSELF AND ELI F. SOUTHWARD,
OF EAST BOSTON, MASSACHUSETTS.

Letters Patent No. 77,695, dated May 5, 1868.

MODE OF HANGING SIGNS OR BANNERS.

The Schedule referred to in these Letters Patent and making part of the same.

TO ALL WHOM IT MAY CONCERN:

Be it known that I, SIMON WING, of the city of Boston, in the State of Massachusetts, have invented a new and-useful Improvement in Signs and Banners; and I do hereby declare the following to be a full and correct description of the same, reference being had to the accompanying drawings, in which the figure represents a suspended sign, made in accordance with my invention.

The nature of this invention consists in forming the ground or foundation of banners or suspended signs, of a net-work or open-work of twine, thread, silk, wire, or other suitable material, and attaching to said ground the required inscription, either in single letters or in strips, the object being to allow the wind to pass through the sign or banner without causing those violent motions which are produced by any considerable breeze in signs made of the ordinary close materials—motions causing the rapid destruction of the sign, interfering with the reading of the inscription, and, by frightening horses, giving rise to serious accidents.

The drawing represents a large sign suspended from a rope stretched across a street. The ground-work is of common fish-net, with large meshes, and this is surrounded by a border, which may be more or less rigid, as preferred. The lettering of the sign is here shown as printed on strips of cloth, which are sewed on to the netting; but, if preferred, each letter may be separately attached to the ground-work, thus offering less surface to the action of the wind, and giving the sign a very light and attractive appearance.

For the smaller projecting banner-signs I prefer to make the ground-work of wire, set in a frame, and use metallic or wooden letters, attached in any convenient mode. Great scope is given, in this method of construction, for variety and elegance of design.

Where signs are to be attached to the edges of awnings, this construction possesses the advantage of offering but slight obstruction to the passage of the light of the street-lamps.

The principle of the invention is applicable to banners intended to be carried in processions, &c. In making these, the ground would be stretched on a suitable frame.

Having thus fully described my invention, I wish it to be distinctly understood that I do not claim the use of bunting, or any other woven fabric, in the manufacture of signs and banners; but

What I claim, and desire to secure by Letters Patent, is—

Making the ground of signs or banners of an open-work or net-work of twine, thread, silk, cord, wire, or other material that will allow the free passage of air, substantially in the manner and for the purpose set forth.

The above specification of my said invention, signed and witnessed at Boston, this 11th day of January, A. D. 1868.

SIMON WING.
